EYELETING MACHINE

Sylvester L. Gookin, Quincy, Mass., assignor to
United Shoe Machinery Corporation, Flemington, N. J., a corporation of New Jersey

Application April 2, 1941, Serial No. 386,482

4 Claims. (Cl. 218—15)

This invention relates to eyelet-inserting machines and is concerned chiefly with a motion for operating both an eyelet-inserting tool and a raceway by which eyelets are presented to the spindle of the inserting tool.

One of the requirements in all types of eyelet-inserting machines in which the eyelets are supplied automatically to an eyelet-inserting tool by a raceway is a raceway-operating mechanism that will postpone placing the delivery end of the raceway in the path of that tool until the latter has been retracted far enough to avoid interference.

To satisfy the timing requirements of the elements the more costly eyelet-inserting machines are provided with operating cams, levers and links that have no duty other than to reciprocate the raceways. On the other hand, some less costly machines have been developed to utilize the reciprocatory motions of the eyelet-inserting tool to operate the raceway, but those machines require supplemental means to postpone the strokes of the raceway with respect to the strokes of the eyelet-inserting tool, because if the strokes of those two elements were synchronized the tool would be unable to pick an eyelet from the raceway at one stage of a cycle and to avoid interference with the raceway at a later stage.

With these conditions in view, an object of the present invention is to provide an improved and simplified eyelet-inserting machine in which the mechanism for reciprocating the eyelet-inserting tool will also reciprocate a raceway with the necessary lag in timing but without any supplemental means to produce such a lag.

The improved operating mechanism includes a crank and a pitman by which the eyelet-inserting tool is reciprocated with a simple rectilinear motion. It also includes a link by which motion is communicated from the pitman to the raceway, and herein lies the solution of the timing problem.

A pitman receives two kinds of motion from a crank, viz., a motion of translation and angular motion about a wrist-pin, but only the first of these is utilized to operate the eyelet-inserting tool. Moreover, the angular motion has its greatest amplitude when the motion of translation has its least amplitude. The invention utilizes both kinds of motion of the pitman to operate the raceway, and the parts that cooperate for this purpose are so related as to utilize the angular movements of the pitman to continue the strokes of the raceway beyond the points at which the re-

versals of direction occur in the movements of translation. Thus, the angular motions throw the strokes of the raceway out of synchronism with the strokes of the eyelet-inserting tool by producing a lag in the movement of the raceway. This lag enables the spindle to pick an eyelet from the raceway at one stage and enables the raceway to avoid interference with the inserting tool at a later stage.

10 Referring to the drawings,

Fig. 1 is a front elevation of an eyelet-inserting machine embodying the present invention, the parts being represented in their initial positions;

Fig. 2 is a front elevation of some of the elements appearing in Fig. 1, but in Fig. 2 the operating shaft has been turned about 25° from its initial position and the eyelet-inserting tool is about to enter an eyelet in the raceway;

Fig. 3 is a front elevation partly in section of the parts included in Fig. 2, but in Fig. 3 the operating shaft has turned about 35° from its initial position and the spindle of the eyelet-inserting tool has been thrust through an eyelet in the raceway;

Fig. 4 is a side elevation of the lower portion of the raceway as viewed from the right hand side of Fig. 3 toward the left;

Fig. 5 is a view of the lower portion of the raceway projected from Fig. 4, the plane of the section being indicated by line V—V in Fig. 3;

Fig. 6 is a side elevation partly in section of starting-and-stopping mechanism by which the shaft of the machine is operated; and

Fig. 7 is a sectional view of the starting-and-stopping mechanism, the section being indicated by line VII—VII in Fig. 6, and the direction of the view being from the rear toward the front of the machine.

40 Referring to Figs. 1, 2, and 3, the eyelet-inserting tool comprises a pressure-applying member 10 and a spindle 11 extending through and projecting from a central bore in the member 10. The member 10 is affixed to a plunger 12 by a set-screw 13, the plunger having a socket to receive the shank of the member 10 and to enclose a compression spring 14 and a follower by which the spindle 11 is normally projected. A head 15 formed on the upper end of the spindle 11 is initially seated against the upper end of the member 10 by the spring 14.

45 A stationary tool 16 located in alignment with the tool 10 is secured in a horn 17 of the frame 18 and is provided with an upsetting shoulder 19 against which the eyelets are driven by the tool

10. A central pilot 20 projecting upwardly from the shoulder 19 is adapted first to locate a previously formed eyelet-receiving hole in a workpiece in the desired position, thereafter to guide the barrel of an ingoing eyelet to the up-setting shoulder 19, and finally to enter the bore in the tool 10. The horn 17 is provided with means 21 by which the tool 16 may be supported and adjusted to locate the shoulder 19 at the desired level.

The plunger 12 is arranged to slide up and down in a bearing 22 afforded by an overhanging portion of the frame 18. The frame also provides horizontal bearings for an operating shaft 25. A crank 26 formed on, or affixed to, the forward end of the shaft is located above the plunger 12 and is operatively connected with the latter by a pitman 27 and a wrist-pin 28. The upper end of the plunger 12 is formed to provide two confronting cheeks between which the lower portion of the pitman is located and through which the wrist-pin 28 extends. The pitman has a laterally extending arm 29 the purpose of which is to carry a pivot pin 30 for communicating motion to the raceway 24 hereinafter described. The arm 29 is formed to provide cooperative portions adapted to be drawn toward each other by a screw 31 to clamp the pin 30.

The raceway is mounted on a supporting pivot 32 located above the shaft 25 and secured in the upper portion of the frame 18. A hopper 33 carried by the raceway may contain a brush or other suitable device for feeding eyelets into the channel 45 of the raceway and such feeding device may be affixed to the upper end of a shaft 34. A pulley 35 secured to the shaft is engaged by a driving belt 36 to operate the eyelet-feeding device. The delivery end 38 of the raceway (see Figs. 4 and 5) is provided with a notch 39 to enable the spindle 11 to be thrust through an eyelet. As shown in Figs. 4 and 5, the eyelet 40 at the delivery end of the raceway is retained therein by a spring-biased detent comprising a member 41, a pin 42 affixed thereto and a small compression spring 43. The member 41 is connected to the raceway by a pivot stud 44 about which it may oscillate when the pin 42 is deflected by an eyelet impaled on the spindle 11. The raceway is so formed as to deliver the eyelets flanged end up as shown in Figs. 3 and 4.

A link 50 is formed and arranged to reciprocate the raceway without lost motion. One end of the link is arranged on the pivot pin 30 and the other end is arranged on a pivot pin 51 carried by the raceway and secured thereto by cooperative clamping portions through which a clamping screw 52 extends. These simple pivotal connections of the link with the raceway on the one hand and the pitman on the other hand maintain a constant distance between the pins 30 and 51 and do away with lost motion, impacts and noise. Since the raceway is located at the left-hand side of the plunger 12 counterclockwise rotation of the shaft 25 is required to produce the correct timing of the raceway with regard to the strokes of the plunger 12. Starting-and-stopping mechanism hereinafter described is organized to arrest the shaft 25 when the crank 26 is at top center, as shown in Fig. 1, and to permit only one revolution of the shaft for each run of the machine.

The timing of the to-and-fro motions of the raceway in relation to those of the plunger 12 will be described with reference to Figs. 1, 2, and 3. In Fig. 1 the crank 26 stands at what

may be termed the zero position; in Fig. 2 it has been turned about 25° from the zero position, while in Fig. 3 it has been turned about 35° from the zero position. Referring again to Fig. 1 the inserting tool 10 stands at the upper limit of its range of travel but the delivery end of the raceway is outside the path of the tool although close to that path. Now, when the crank 26 is turned to the position represented in Fig. 2 its movement will complete the interrupted travel of the delivery end of the raceway from left to right and thereby place the eyelet 40 in register with the spindle 11. At the same time, the crank will depress the plunger 12 very little but far enough to place the tip of the spindle at the same level as the upper end of the eyelet 40. Although this movement of the crank produces a slight downward movement of translation of the pitman 27 it also produces a relatively great component of angular movement about the wrist-pin 28. At this stage of a cycle the amplitude of angular movement is greatest and the movement of translation is least and in consequence of this disparity the pivot pin 30 moves upwardly despite the downward movement of the wrist-pin 28. The result is that the delivery end of the raceway completes its travel to the right about 25° after the tool 10 begins its down-stroke.

As the shaft 25 continues to rotate from the position represented in Fig. 2 to that represented in Fig. 3 the movement of translation of the pitman 27 accelerates while the angular movement about the wrist-pin 28 decelerates, with the result that the tip of the spindle 11 is thrust through the eyelet 40 at a stage when the movement of the raceway is almost negligible. Nevertheless, while the crank is moving from the position shown in Fig. 2 to that shown in Fig. 3 the angular movement of the pitman about the wrist-pin 28 is not quite sufficient to counteract the movement of translation, and the result of this disparity is that the pivot pin 30 moves downwardly but with less amplitude of downward component than the wrist-pin 28. Consequently, while the tip of the spindle 11 is traveling through the eyelet 40 with increasing speed the delivery end of the raceway is retracted far enough to carry the retaining pin 42 past the barrel of the eyelet and to remove about one-half of the diameter of the eyelet from the raceway. (See Fig. 3.) As the shaft 25 continues to rotate beyond the position represented in Fig. 3, the raceway moves to the left with increasing speed, thereby clearing the path of the tool 10. The raceway remains out of the path of the tool 10 through the remainder of that cycle of the shaft 25, although it is brought back to the position shown in Fig. 1 after the tool has risen far enough to clear it.

The starting-and-stopping mechanism includes a friction clutch the driving member of which is a V-belt 53 and the driven member of which includes a circular disk 54 having an annular surface 55 arranged to engage one side of the belt. The disk 54 is mounted on the shaft 25 and is connected thereto by splines 56, Fig. 7, which enable the disk to be shifted axially to and from engagement with the belt. The inner surface of the belt runs on a flange 57 of an idle pulley 58 loosely mounted on a bearing sleeve 59 affixed to the shaft 25. A flange formed on one end of the sleeve and a collar affixed to its other end prevent axial movement of the pulley. This pulley also has a shoulder arranged to engage the other side of the belt opposite the annular

surface 55 of the driven member. The driven member of the clutch also includes a hub 60 in which three sockets are bored for the reception of compression springs 61. As shown in Fig. 6, the right-hand ends of these springs are seated on a shoulder of the hub while the left-hand ends are seated on a cam 62 affixed to the shaft 25. The effect of the springs is to force the annular surface 55 of the driven member against the belt 53 to establish a driving engagement.

The belt is driven continuously and the idle pulley 58 rotates continuously in conformity therewith while serving to maintain a segment of the belt in concentric relation to the annular surface 55. Automatic retraction of the disk 54 from the belt is effected by an arcuate flange 63 formed on the hub 60 and provided with a wedging surface 64 arranged to cooperate with a starting-and-stopping rod 65. The trailing end of the flange 63 is provided with a stop shoulder 66 arranged to abut the rod 65 to arrest the rotation of the shaft when the crank 25 is at top center, as shown in Fig. 1, but while the wedging face 64 of the flange is traversing the rod 65 it disengages the annular surface 55 from the belt.

The rod 65 is arranged to slide vertically in bearings bored in the frame 18 and its upper end is normally maintained in the path of the flange 63 by a compression spring 67. The lower end of this spring is seated on a portion of the frame 18 and the upper end abuts a collar 68 affixed to the rod. Another collar 69 is affixed to this rod to limit its upward movement by engagement with a portion of the frame 18.

The means for depressing the rod 65 out of engagement with the flange 63 comprises an operating rod 70 also arranged to slide up and down in bearings bored in the frame 18. 71 represents a treadle rod forming an operating connection between the rod 70 and a treadle (not shown). The rod 70 is normally raised by a compression spring 72 and its upward movement is limited by a collar 73 affixed thereto and arranged to abut a portion of the frame 18. A bracket 75 affixed to the rod 70 carries an arm 76, the lower end of which is connected thereto by a pivot pin 77 and the upper end of which is arranged to cooperate with the cam 62. A lug 78 formed on the arm 76 initially overlaps the collar 68 on the rod 65 and is normally maintained in that relation by a leaf-spring 79 affixed to the bracket 75.

When the operating rod 70 is depressed by the treadle its downward movement is communicated to the starting-and-stopping rod 65 by the lug 78 and the collar 68. The upper end of the rod 65 is thus disengaged from the flange 63, whereupon the springs 61 shift the driven member of the clutch into engagement with the belt 53. During the first 180° rotation of the shaft 25 the cam 62 actuates the arm 76 to disengage the lug 78 from the collar 68 and in consequence thereof the spring 67 returns the upper end of the rod 65 into the path of rotation of the wedging element 63, the rod 65 being no longer under control of the rod 70. During the remainder of this cycle of revolution the wedging element 63 traverses the rod 65 thereby disengaging the driven disk 54 from the belt 53 and finally bringing the stop shoulder 66 into engagement with the rod 65. The operator need not release the treadle until

he desires to do so, but when the treadle is released the compression spring 72 will raise the

arm 76 far enough to carry the lug 78 above the upper end of the collar 68, whereupon the lug will be returned to its overlapping position by the leaf-spring 79 and the starting-and-stopping mechanism will thus be restored to its initial condition in readiness for a repetition of the cycle.

Having thus described my invention, what I claim as new and desire to secure by Letters Patent of the United States is:

10. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
15. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
20. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
25. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
30. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
35. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
40. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
45. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
50. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
55. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
60. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
65. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.
70. An eyeleting machine comprising a plunger, an eyelet-inserting tool carried thereby, said tool having a spindle to impale an eyelet, an eyelet-raceway the delivery end of which is movable to and from the path of said tool, a crank arranged to reciprocate said plunger, a pitman by which said crank and said plunger are connected, and means carried by said pitman for moving said raceway to and fro in cooperative relation to said spindle without lost motion, said means being arranged to utilize the angular movement of said pitman to move the delivery end of the raceway into the path of said tool when said crank is adjacent to its dead-center position at which said plunger is fully retracted.

SYLVESTER L. GOOKIN.
